(57) **CLAIM**

The ornamental design for a rib pet treat, as shown and described.

DESCRIPTION

FIG. 1 is a front, top, and right side perspective view of a rib pet treat according to the new design;

FIG. 2 is a front, bottom and right side perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines shown in FIGS. 1–6 and 8 illustrate portions of the rib pet treat that form no part of the claimed design.

1 Claim, 6 Drawing Sheets
